GEORGE B. THOMAS, OF BRIDGEPORT, CONNECTICUT, ASSIGNEE TO THE BRYANT ELECTRIC COMPANY, OF BRIDGEPORT, CONNECTICUT, A CORPORATION OF CONNECTICUT.

ELECTRIC-LAMP SOCKET.

1,231,456.

Specification of Letters Patent. Patented June 26, 1917.

Application filed January 20, 1916. Serial No. 73,002.

To all whom it may concern:

Be it known that I, GEORGE B. THOMAS, a citizen of the United States of America, and residing at Bridgeport, in the county of 5 Fairfield and State of Connecticut, have invented a certain new and useful Improvement in Electric-Lamp Sockets, of which the following is a specification.

My invention relates to electric lamp 10 sockets and particularly to sockets for incandescent lamps, the object of my invention being to provide an improved holding device and receiving contacts for lamps of the Edi-Swan type.

15 In the accompanying drawing,

Figure 1 is a vertical section through a lamp socket in which my invention is embodied in one form;

Fig. 2 is a detached broken elevation 20 thereof;

Fig. 3 is a transverse section on the line 3-3, Fig. 1;

Fig. 4 is a plan showing the manner in 25 which the insulating disk is adjusted between the lamp-receiving contacts;

Fig. 5 is a dropped perspective of the holding shell and lamp base;

Fig. 6 is a plan of the insulating body of 30 the socket alone; and

Fig. 7 is a plan of the opposite end of 35 the socket body with the metal parts removed.

The present invention is here illustrated 40 in a socket of switchless type, but it will be understood that the improvements herein-after set forth, may be applied to a switched socket with only such minor changes of connection to the socket terminals as are necessitated by the interposition of a switch mechanism between the wire terminals or 45 one of them and the socket terminals or one of them. Since the invention does not relate to these particular connections they are not here shown or described.

As illustrated, the socket comprises an insulating body, here in one piece, 10, recessed on opposite sides at its inner end to form lateral bays 11 and 12 in which are located the wire terminals 13 and 14 respectively. At the outer or lamp-receiving end of the socket, the block 10 is recessed adjacent opposite margins to afford seats 15 and 16 for the bases 17 and 18 of the 50 socket terminals 19 and 20. These terminals comprise circumferentially spaced over-

lapping helices of flat spring metal preferably integral with their bases 17 and 18 but sprung away therefrom and from each other. The seats for the bases of the socket terminals are alined with the wire terminal bays 60 so that the securing screw bolts 21 and 22 which hold the wire terminals in place also secure the socket terminals on the outer face of the insulating body and afford electrical connection between the same. A second pair of marginal seats 23-24 spaced from the terminal seats, receive the offset bases 25, 26, of the legs 27, 28, struck from the side walls of the lamp-supporting shell 29. Screw bolts 30 and 31 piercing the 70 block take into these tapped bases and hold the shell fast to the block.

When a lamp 32 is inserted in the socket, its two contacts 33, 34, engage the spring terminals 19 and 20 and establish the circuit through the lamp. As the lamp is pushed in however, it compresses these helical terminals and brings them into such close proximity that there is danger of their contacting with each other and thus shorting 80 circuiting the lamp. To eliminate this danger I provide a disk 35 of insulating material such as paper, fiber, mica or the like, which is interposed between the overlying portions of the helices and insures their 85 separation and electrical isolation even should they be pressed hard down against the socket body by the inserted lamp. This disk is radially slotted at 36, 37, to permit the ends of the terminals to pass therethrough, while arcuate slots 38 and 39 communicating therewith form tongues 40 and 41 in the disk which are distorted downward beneath the respective terminals when the disk is in adjusted position. The 90 method of assembling the disk with relation to the terminals is shown in Fig. 4, the arrows indicating the direction of rotation of the disk after the ends of the terminals have been inserted through the radial 95 slots 36, 37. The fully adjusted position is shown in Fig. 3, where it will be seen that the exposed end of terminal 19 is not only spaced circumferentially from the exposed end of terminal 20, but also that the portion of the disk underlying the exposed end of terminal 19 separates the latter from the subadjacent portion of the terminal 20 and vice versa.

In order to accurately position the disk 110

- in its adjusted position and hold it against accidental displacement, I provide it with opposite marginal ears 42, 43, which are engaged and confined by notches 44, 45 in the inner edge of the shell 29. The position of these notches is of course predetermined with relation to the size and position of the terminals so that the disk occupies substantially the position shown in Fig. 3.
10. A surrounding casing for the socket is also provided, which comprises a cap 46 and shell 47 sleeving therewith and provided with readily detachable latching devices 48 and 49 within the sleeving area.
15. The cap is provided with the usual threaded bushing 50 for attaching the fitting to a wire conduit, while the shell has near its outer end a threaded bead 51 adapted to receive a shade holder. To prevent the 20 socket body from swiveling in the casing during the adjustment of the lamp, I provide the block 10 on opposite sides with channels 52, 53, into which take projections 54, 55 on the shell. These projections are 25 here formed by striking inwardly tongues of metal, preferably within the sleeving area of the shell and cap so that the appearance of the assembled fitting is not marred thereby. The casing is also inwardly offset at 30 56 to form a shoulder which engages beneath the peripheral ledge 57 on the block and thus prevents endwise separation of the socket body and its casing. A lining 58 of insulating material may be interposed 35 between the shell and cap to provide against any possible danger should the supporting shell, through some unforeseen contingency, be brought into the circuit.
- The usual studs 59 and 60 on the lamp 40 base engage the bayonet slots 61 and 62 in the shell on the insertion of the lamp while the outward pressure of the spring terminals 19 and 20 holds the studs firmly in position.
45. Various modifications in details of construction will readily occur to those skilled in the art which do not depart from what I claim as my invention.
- I claim as my invention:—
50. 1. An electric lamp socket having a pair of superposed helicoidal lamp-engaging terminals and insulating means interposed between the spires of said terminals to insure their insulation from each other.
55. 2. An electric lamp socket having a pair of circumferentially spaced, superposed, helicoidal lamp-engaging terminals and insulating means interposed between the spires of said terminals to insure their insulation from each other.
3. An electric lamp socket having a pair of superposed helicoidal lamp-engaging terminals and insulating means interposed between the spires of said terminals to insure their insulation from each other, together with means to maintain said insulating means in adjusted position.
4. An electric lamp socket having a pair of superposed helicoidal lamp-engaging terminals and insulating means interposed between the spires of said terminals to insure their insulation from each other, said means comprising a split disk through which the lamp-engaging ends of the terminals pass.
5. An electric lamp socket having a pair of superposed helicoidal lamp-engaging terminals and insulating means interposed between the spires of said terminals to insure their insulation from each other, said means comprising a split disk through which the lamp-engaging ends of the terminals pass, a lamp supporting shell surrounding said terminals and lugs on the insulating disk engaging said shell to hold the disk in adjusted position.
6. An electric lamp socket having a pair of lamp-engaging terminals, a lamp supporting shell surrounding the same, outwardly bowed legs struck from the wall of said shell and offset lugs at the free ends of said legs tapped to receive securing screws.
7. An electric lamp socket having a pair of superposed helicoidal lamp-engaging terminals, an insulating body carrying the same, a lamp supporting shell surrounding said terminals and secured to said body, said shell being notched at its inner edge, a split insulating disk interposed between said terminals and through which the lamp-engaging ends of the terminals project, and marginal ears on said disk engaging in the notches in the shell to hold the disk in adjusted position.
- In testimony whereof I have signed my name to this specification, in the presence of two subscribing witnesses.
- GEORGE B. THOMAS.
